IMPELLER STRUCTURE

Joe R. Urschel, 158 S. Napoleon St., Valparaiso, Ind.
Filed Oct. 1, 1959, Ser. No. 843,779

5 Claims. (Cl. 146—124)

This invention has to do with meat grinding or cutting machines in which an impeller is used for revolving the meat within a comminuting chamber therefor, and more particularly concerns improvements in the impeller structure. This application is a continuation-in-part of my co-pending application Serial No. 359,915, filed June 5, 1953, for Meat Comminuting Machine which became Patent No. 2,938,558 on May 31, 1960.

An important object of this invention is the provision of a novel impeller structure having prong-like impeller elements with meat hooking faces intersecting other faces to form meat shearing edges cooperable with the chamber wall to comminute the meat as it is revolved in the chamber by and with the impeller elements attendant to impeller structure rotation.

A further object is the provision of impeller elements adjustable radially of a rotatable carrier head therefor of the impeller structure, together with means for holding such elements at selectively different radial positions, thereby adapting the elements to be set radially outward after their shearing edges become dull and to be thereafter sharpened by rotation of the structure and grinding back the edges to a common radius from the head axis to properly space these edges from the chamber wall.

These and other desirable objects inherent in and encompassed by the invention will be elucidated in the ensuing description, the appended claims and the annexed drawings, wherein:

FIG. 1 is a side view partly in elevation and partly in section of a meat comminuting machine of a character in which an impeller structure made according to the present invention is useful.

FIG. 2 is an enlarged perspective view of a five element impeller structure constructed according to the present invention and used in the comminuting chamber of the machine shown in FIG. 1.

FIG. 3 is a fragmentary sectional view taken substantially on the line 3—3 of FIG. 2.

FIG. 4 is an enlarged fragmentary sectional view taken on a plane coinciding with the principal axis of the comminuting chamber of FIG. 1 and as indicated by the line 4—4 of FIG. 1.

FIG. 5 is an enlarged fragmentary view of the inner periphery of the chamber wall wherein ribs between meat discharge passages have a knife edge form of meat cutting means thereon.

FIG. 6 is a fragmentary sectional view taken on the line 6—6 of FIG. 5.

FIG. 7 is a fragmentary sectional view taken on the line 7—7 of FIG. 5.

FIG. 8 is a fragmentary sectional view taken on the line 8—8 of FIG. 3.

A base 131 for the machine shown in FIGS. 1 and 4 supports a cylindrical housing 132 mounted thereon with its principal axis inclined at an angle of substantially 45°. Housing 132 has an electric motor 133 mounted coaxially therein. Motor 133 is shown by dotted lines in FIG. 1 and the upper portion thereof is shown in full lines in FIG. 4. The armature shaft 134, FIG. 4, of the motor is journaled in an upper end wall 135 of the cylindrical housing 132 by means of a ball bearing unit 136. A reduced diameter and threaded upper end portion of the armature shaft 134 is designated 137 and is turned into a threaded bore 138, FIG. 2, of an impeller head 139.

The head 139 of the impeller 141 contains five radial

2

notches 142 spaced equiangularly with respect to the principal axis of this base. Each notch communicates radially outwardly through the cylindrical periphery of the impeller head and also communicates upwardly

5 through the upper flat face of such head. In FIG. 3 it can be seen that one of the notches 142, which is identical in structure with each of the others, has a bottom wall 143 containing a slot 144 extending radially of the rotor head 139. Each notch 142 slidably receives the base 145 of an impeller element 146. Each impeller element comprises an upwardly extending prong portion 147 having a shearing edge 148 formed at the intersection of an outer face 149 with an upright face 151 and a forwardly inclined hooking face 152. The base of each impeller element 146 has a threaded recess 153 in the bottom thereof into which there is threaded a shank 154 of a cap screw 155. The threaded shanks 154 of these cap screws are received by the radial slots 144 and are adjustable lengthwise thereof radially of the impeller head 139 pursuant to adjusting the impeller elements 146 radially of the head 139. When it is desired to resharpen the impeller element cutting edges 148, such elements are adjusted a few thousandths of an inch radially outward, and thereafter the entire impeller head assembly is rotated about its axis while the cutting edges are sharpened by grinding back to lie within a common cylindrical path of a radius to properly space these edges from the chamber wall. Such a cylindrical path is represented in transverse section by the circular dot-dash line CXR in FIG. 8 where it is shown the outer face 149 of the impeller element 146 there shown is disposed at an exterior angle in excess of 270° with respect to the upright face 151 to cause the shearing edge 148, seen as a point, to be the apex of an acute angle. It can also be seen in FIG. 8 that the outer face 149 is disposed chordally of the cylindrical path coincident with the line CXR.

The cylindrical rotor head 139 is received coaxially within the lower portion of a cylindrical inner periphery 157 of a comminuting chamber 158. The lower portion 40 of the cylindrical inner periphery 157 is within a base portion 159 of the chamber 158. The bottom of this base 159 rests upon the upper end of the housing end wall 135 to which it is secured by clamping members 161 spaced circumferentially thereabout (one being shown in FIG. 1 and another in FIG. 4) and secured to the end wall by cap screws 162. A lower cylindrical portion 163 of a side wall 164 extending upwardly from the base 159 and also containing said cylindrical inner periphery 157 45 contains a plurality of discharge passages 165 extending radially therethrough. As shown in each of FIGS. 1, 4 and 5, these side wall passages 165 are elongated circumferentially of the cylindrical wall portion 163 and are each provided with circumferentially spaced narrow extremities 166 and 167. Meat deposited within the chamber 158 is revolved counter-clockwise therein with the impeller 141 as viewed from above in FIG. 4. Therefore, the meat as it is revolved in the chamber 158, is pressed centrifugally against the inner periphery 157 of the chamber side wall portion 163. The meat therefore approaches each of the passages 165 at the extremities 166 and departs therefrom at their extremities 167. These extremities 167 are in the form of cutting edges within the inner periphery 157 of the side wall portion 163, and such cutting edges would therefore be departure edges in the sense that they are the edges at the ends of the passages 165 from which the revolving meat departs from these passages. Each passage 165 also has a narrow impact side 168 which intersects the side wall inner periphery 157 coincidentally with the departure edge 167 thereof, FIG. 7.

Each of the slot-like discharge passages 165 is formed

by cutting into the outer periphery of the chamber wall 163 by a milling wheel not shown having a circumferential profile conforming to the circle CIR, FIG. 7. When the milling wheel is advanced radially inwardly with respect to the wall 163 to cut the opening 165 associated therewith to be of proper length circumferentially of the wall 163, narrow opposite sides 168 and 170 of the resulting passage will have concave curvature conforming to the circle CIR. The concave narrow side 168 is the impact side mentioned hereinabove.

As is visible in each of FIGS. 1 and 4 the passages 165 are grouped in respective series SER of such passages, the passages in each series being in lateral juxtaposition axially of the chamber side wall 163, and each series of passages extending axially of the chamber. Portions of the wall 163 between the passages 165 in each series SER are in the form of ribs 169 of less transverse width axially of the chamber than said passages, said ribs forming boundaries for long edges of said passages 165 and constituting separating means therebetween. Meat cutting means on the sides of said ribs 169 facing inwardly of the chamber 158 may be in the form of sharpened edges 171 on the inner edges or sides of said ribs facing inwardly of the chamber as illustrated in the species of FIGS. 5 and 6. It is preferred, however, to provide cutting means on the inner sides of the ribs 169 by forming notches 172 therein as illustrated in FIG. 7 with the effect of forming shoulders 173 and slitting teeth 174.

A downwardly flared inner peripheral portion 175 of the chamber wall 164 is adapted to guide meat downwardly into the cylindrical peripheral portion 157 of the chamber wall. Immediately above the downwardly flared conical periphery 175 is a cylindrical internal wall periphery 176 which is of the same diameter as the cylindrical internal periphery of a feeding tube 177, mounted in the lower end of a feeding spout 178 formed integrally with a hopper tray 179. The lower end of the feeding tube 177 removably rests upon a seat 179a on the upper end of the chamber side wall 164. In FIG. 1 the hopper tray 179 can be seen to be pivotally connected with a rear wall 181 of a ground meat receiving apron 182 by means of a pivot pin 183 extending through laterally spaced apertured studs 184 (one being shown) on said wall 181 and through an apertured ear 185 depending from the lower side of the hopper tray 179 between the studs 184. The apron 182 is mounted upon a circular flange 186 at the upper end and of the motor housing 132 by means of machine screws 187.

Operation of the machine

With the machine arranged as shown in FIG. 1, that is, with the hopper tray 179 pivoted counter-clockwise into the horizontal shown whereby the lower end of the feeding tube 177 rests upon the seat 179a at the upper end of the chamber 158, pieces of meat suitable for cutting into hamburger or a similar product (not shown) are placed in the hopper tray preparatory to being fed downwardly through the spout 178. Thereupon a control switch handle 188 on the side of the base 131, FIG. 1, is manipulated conventionally for energizing the electric motor 133. Thereupon the armature shaft 134 of the motor together with the impeller 141 is caused to rotate counter-clockwise as viewed from their upper ends. This causes counter-clockwise revolving motion of the prong-like impeller elements 146 within the meat receiving chamber 158 whereby the cutting edges 148 of these impeller elements are swept contiguously with and about the cylindrical inner periphery 157 of the chamber side wall portion 163 containing the passages 165. As the meat is fed downwardly through the spout 178, the feeding tube 177, the cylindrical periphery portion 176 of the chamber side wall portion 164 and through the downwardly flared conical wall periphery 175 into the lower part of the chamber where the meat is engaged by the

revolving impeller elements 146, such impeller elements upon engaging the meat cause it to revolve therewith. Centrifugal force of the revolving meat upon the downwardly flared wall surface 175 develops a downward force vector tending to pull the meat downwardly through the feeding passage including the tube 177 into the lower part of the chamber 158. Frictional engagement of the revolving meat with the cylindrical inner periphery 157 of the chamber 158 develops a reaction force upon the inclined hooking faces 152 of the prong-like impellers 146 thereby developing a further downward force vector upon the meat for supplementing the force of gravity in causing downward movement of the meat within the chamber 158.

As the meat is thus revolved within the lower cylindrical portion of the chamber 158, surface portions thereof bulge outwardly into the passages 165 and are trimmed or snipped off from the main body portion of the meat within the chamber by cooperation of the cutting edges 148 of the impellers with the departure edges 167 of the passages 165. When the passages 165 are relatively narrow to cause the removal of meat particles of a size suitable for forming hamburger meat, these particles as they are sheared off at the departure edges 167 are dashed against the impact sides or surfaces 168, FIG. 7, of the passages 165. Such collision of the cut-off meat particles with the impact surfaces 168 breaks down the cell walls of the meat to increase its tenderness. The meat slitting means 174 or 171 on the inner sides of the ribs 169 prepare the meat so it passes through the machine more quickly and with less heat generation.

Meat discharged from the discharge passages 165 flows onto the apron 182 from which it is easily discharged, because of the sloping position of this apron, into a suitable receptacle (not shown) below the lower left hand edge of this apron.

Having described a preferred embodiment of the invention with the view of completely and concisely illustrating the same, I claim:

1. For use in a meat-receiving chamber of a meat comminuting machine, a meat impeller structure comprising a head rotatable about an upwardly extending axis, a plurality of prong-like meat impeller elements spaced circumferentially about said axis and projecting axially upwardly from said head, the elements being revolved about said axis attendant to rotation of the impeller structure about said axis, each impeller element having an upwardly extending outer face on the side thereof opposite from said axis, a meat propelling face extending upwardly from said head and facing in the direction such element is revolved during impeller structure rotation, a hooking face extending upwardly from said propelling face and also facing in the direction such element is revolved during impeller structure rotation but said hooking face being at an angle to the propelling face and facing downwardly, and the propelling and hooking faces of each element intersecting said outer face thereof to form therewith a shearing edge.

2. The combination set forth in claim 1, wherein said outer faces of the impeller elements are disposed at an exterior angle in excess of 270° with their respective propelling and hooking faces to cause said shearing edges to be the apex of an acute angle.

3. The combination set forth in claim 2, wherein the propelling and hooking faces of the elements extend substantially radially of the impeller structure axis, to dispose said outer faces chordally of a cylindrical path generated about said axis and intersecting said shearing edge.

4. For use in a meat-receiving chamber of a meat comminuting machine, a meat impeller structure comprising a head rotatable about an upwardly extending axis, a plurality of prong-like meat impeller elements spaced circumferentially about said axis and projecting axially upwardly from said head, the elements being

revolved about said axis attendant to rotation of the impeller structure about said axis, each impeller element having an upwardly extending outer face on the side thereof opposite from said axis, a meat hooking face extending upwardly with reference to said head and inclining and facing in the direction such element is revolved during impeller structure rotation, and said hooking face intersecting said outer face to form there-with a shearing edge.

5. The combination set forth in claim 4, wherein the 10 impeller elements are adjustable radially of the head,

and wherein there is means for holding said elements upon the head at selectively different positions radially thereof.
